Specification of Letters Patent. Patented July 23, 1912.

Application filed August 4, 1908. Serial No. 446,840.

To all whom it may concern:

Be it known that I, LEWIS E. MORRISON, a citizen of the United States of America, and a resident of Newark, Essex county, New Jersey, have invented certain new and useful Improvements in Printing-Machines, of which the following is a specification.

This invention relates to printing machines and has particular reference to improvements in machines for printing and handling envelopes.

The objects of the invention are to provide simple and automatically operated mechanisms for printing a single envelop or two envelopes at the time; to provide a novel tripping mechanism, whereby the press will be tripped when an envelop fails to reach the platen; to provide novel registering means for the envelopes and to provide means for separating the unprinted from the printed envelopes.

Other objects will appear as this specification proceeds.

Some of the mechanisms which contribute to accomplish the various results obtained by this invention have already been described by me in several applications, the filing dates and serial numbers of which are as follows. One application filed February 25, 1908, Ser. No. 416,203; another application filed February 27, 1908, Ser. No. 418,021; a third application filed March 6, 1908, Ser. No. 419,480; and a fourth application filed March 26, 1908, Ser. No. 423,395.

In the present instance it will be seen that the scope of the inventions contained in the above applications have been extended and the constructions improved, also that several new features have been added in order to 40 make the machine wholly automatic and perfect in its operation.

To this end my invention comprises such features and parts of construction and co-operation as will hereinafter be fully described in detail while reference is had to the accompanying drawings in which—

Figure 1 is a side elevation of a printing press embodying my invention, with parts omitted; Fig. 2 is a detail view showing the foot of the press; Fig. 3 is a perspective view showing the separating and feeding mechanisms with adjacent parts; Fig. 4 is a detail view of the registering means; Figs. 5 and 6 are front and side views of parts of the separating mechanism; Fig. 7 is a dia-

grammatic view showing the wiring for the electrically operated tripping means; Figs. 8 and 9 are detail views of parts of the mechanism for separating the printed from the unprinted envelopes; Figs. 10 and 11 are detail views of the receptacle for the printed envelopes. Fig. 12 is a view of one of the grippers; Figs. 13, 14 and 15 are enlarged detail views of parts shown in Figs. 8 and 9, and Fig. 16 shows a registering frame used for a single envelop.

In the drawings, I have shown my invention applied to a machine commonly known in the art as a platen press or job press, and one of the objects of my invention is to so construct the various improvements that they may readily and quickly be attached to the job press without necessitating changes in the construction of the same; at the same time it should be distinctly understood that my invention or parts thereof may be used on other machines as well.

Referring to Fig. 1, the numeral 1 denotes the frame of the press, 2 is the platen while 3 is the form member which is pivoted at 4, (see Fig. 2) and oscillates in the usual manner by means of the connecting rods 5 of which there is one on either side of the press. The one connecting rod is pivoted at 6 to the disk 7, while the other is pivoted in similar manner on the other side of the press to the gear 8 which is driven from pinion 9 in main shaft 10. The platen 2 oscillates also as is usual in presses of this type and it is not necessary to describe the parts which accomplish this result as they form no element in this invention. In front of the platen on either side of the press is fastened two brackets 11 which support the separating and feeding mechanisms with adjacent parts.

The envelop separating mechanism (see Fig. 3) comprises a support formed by the two sides 12 joined by the transverse piece 13. The sides 12 are suitably fastened to the brackets 11 with screws or bolts, not shown. A smaller framework comprising levers 14 and the slotted bar 15 is pivoted at 16 on the sides 12. Adjustably fixed on the bar 15 by bolts 16 are the envelop supporting means of which there are two end supports 17, which are alike and one center support 18. Between these supports the envelopes are laid in two piles with the flaps downward. Each end support comprises a

2
wing or ear 19, (see Figs. 5 and 6) through which passes the bolt 16^a. The ear 19 is integral with the upright 20, the bottom of which is bent to form the ridge 21 and which also carries laterally extended shelves 29. Two transverse ears 22 and 23 are also integral with the upright 20 and serve to support the L piece 24. By adjusting the supports along the bar 15, these L pieces form sort of pockets in which the envelopes lie as seen in Fig. 6, the corners of the envelopes resting in the L pieces, and upon the shelves 29. The pieces 24 are vertically adjustable with relation to the ears 22 and 23 by means of the slot and screw 25 and 26, and the screw 27 which serves to force the L down against the spring 28. By these means the space 30 between the bottom of the L and the ridge 21 may be adjusted so as to permit of the passage of different thicknesses of envelopes.

The center support 18 is constructed substantially as above, except that it comprises an upright 20 which in turn supports two L's 24 adjustable in the same manner as aforesaid.

A slide 31 is provided which slides on the side frames 12 by means of shoes 32 and which carry fingers 33 which are adapted 30 to enter between the envelop and its flap and push the two single bottom envelopes side by side out through the aforesaid spaces 30. The slide 31 has pivoted thereto at both ends links 34 pivoted to levers 35 which are pivoted at 36 to the brackets 11. It will be readily seen that in case only one envelop is to be printed at a time, the center support 18 will be removed and the single pile of envelopes supported between and on the supports 17 which will then be properly adjusted along the bar 15. After the envelopes have been pushed from under the piles they fall on the feeding mechanism. This mechanism comprises two arms 37 journaled 40 on shaft 38 in the brackets 11 and carrying at their free ends another shaft 39. Over these two shafts pass tapes 40 which are driven constantly in the direction toward the shaft 39 by a train of gears 41, 42, 43 45 and 44 which are carried by the one arm 37 and of which the gear 44 meshes with the gear 8 which normally belongs to the press. A shaft 45 supports the stops 46 adjustably carried thereby by set screws as shown. 50 This shaft 45 is rocked periodically by means of arm 46', link 47, bell crank 48, link 49 and lever 50, which latter is pivoted at 51 on the one bracket 11 and carries a cam roll 52 running on the usual platen locking cam 53. Side guides 54 are adjustably carried in the arms 37 and when two envelopes are to be printed at once, a center guide 55 is added which is adjustably carried by a rod 56 supported in the saddles 60 65 57 which fit over the rods 58 which support

the outside guides 54. In this manner the side and center guides may be adjusted to suit the size of the envelops. At the ends of the guides are fastened wings 59. The envelops after having been separated, 70 fall on the tapes 40 and are conveyed downwardly toward the platen, until they strike the stops 46, the ends of which rest on the shaft 39. At the proper time the cam roll 52 will run on the low part of the cam 53, 75 the stops will be raised and the envelopes passed from the tapes and under the wings 59 to the platen 2.

After the envelopes leave the tapes, the feeding mechanism is raised on the pivot 38, 80 to permit the platen to move downwardly into printing position, and to this end the following means are provided: Each arm 37 carries a cam 60 which rests on a roller 61 mounted on the levers 62, pivoted at 63 on the brackets 11. The levers 62 rest in turn on rollers 63', fastened to the platen, so that, as the latter oscillates, the levers 62 swing around their pivots and oscillate in turn the feeding mechanism. For the purposes of 85 making ready or otherwise getting at the press, the feeding mechanism may be swung upward around the shaft 38, after the bar 15 has been laid down as indicated in dotted lines. On the platen is detachably fixed the 90 registering mechanism. This comprises two side bars 64, having the angularly bent ends 65 which hook over the edges of the platen. The bars are joined by the transverse strip 66 which carries thin brass pieces 67, the upturned ends 68 of which form stripping fingers while a part is turned down angularly and rests on the platen to form stops 69. A central dividing tongue 70 extends in 95 under and through the central wing 59, of 100 the feeding mechanism. The bars 64 carry side guides 71 which are adjustable by slot 72 and screws 73. After the envelopes leave the tapes 40, they pass under the wings 59 and onto the platen 2, against stops 69, the 105 sides of the envelopes being guided between the guides 71 and the center tongue 70. Next the printing takes place and when the form member leaves the platen, the ends 110 68 which are springy, serve to strip the envelopes from the form. The registering mechanism may easily be detached from the platen by prying the ends 65 of the bars 64 over the edges thereof, and in Fig. 16, I have 115 illustrated a single envelop registering frame, which is built like the one aforesaid, except that the central piece 67 and dividing tongue 70 are absent. By inspecting this figure, the simplicity of this construction and the ease of attachment to and detachment from the platen will be apparent. After the printing has been completed, the platen again moves upwardly and the printed envelopes are removed by means of the delivery grippers. See Fig. 12. The gripper 120 125 130

is composed of a lower jaw 75 on which is pivoted the upper jaw 76. A spring 77 is inserted between the jaws and normally closes the same. A locking slide 78 is carried on the lower jaw and is under a steady pull of the spring 79 toward the tail end 86 of the upper jaw 76. The locking slide also carries the rod 80 which by contact with the edge of the platen causes the gripper to close 10 by action of the flat spring 77. The grippers are carried on the slotted bar 81, shown in Figs. 3 and 12 in the usual fashion by thumb screws so as to be capable of adjustment along said bar, which constitutes a gripper carriage adapted to slide on the lever 62, and which is operated by the levers or arms 82, pivoted at 83, at the foot of the press, see Fig. 2.

When the platen moves upwardly the grippers are moved to the rear or left as seen in Fig. 1 and in the open position shown in Fig. 12, at the end of the stroke of the lever 82 the rod 80 abuts the edge of the platen, this forces the locking slide 78 away from 25 the upper jaw which closes on the envelop under the action of the spring 77. Next the grippers move to the front or right and at the proper time the high part 84 of the upper jaw 76 is brought in engagement with 30 the transverse rod 85, see Figs. 1 and 3; this causes the gripper to open, the envelops are dropped therefrom and the locking slide 78 under the pull of the spring 79 snaps over the tail end 86 and keeps the gripper open.

35 The transverse gripper opening rod 85 is adjustably mounted in the slots 87 of the blocks 88, which are mounted one on each side on the oscillating levers 62. In this manner a close co-operation between the separating and feeding mechanism, the platen and the grippers is assured and the necessary adjustment provided for.

40 The operating means for the levers 82 for the grippers are as follows: To the connecting rod 5 on the right side of the press is pivoted a link 89, see Fig. 1, the other end of which is pivoted at 90 to the said lever 82, so that this latter is oscillated as the form member is moved back and forth, and the 45 levers 35 which operate the separating mechanism have their free ends joined by a rod 91 which is kept in contact with the levers 82 by a spring 92, see Fig. 1, so that as the levers 82 move to the right, the upper ends 50 of levers 35 are moved to the left and vice versa, an adjustable stop 93, Fig. 3, is provided which limits the stroke of the levers 35 and further movement by the levers 82 is taken up by the said spring 92 between the 55 two sets of levers.

60 When the grippers open the envelops are dropped into the envelop receptacle shown in Figs. 1, 8, 10 and 11. This receptacle is made up of two side walls 95 and a center wall 96, all joined by the elevated transverse

bottoms 97, which are suitably formed and are supported by the bent flat irons 98. The lower and forward ends of these latter support the inclined flaps 99.

The envelop receptacle is set down in and supported by the sheet receptacle which comprises the flat bottom 100 provided with adjustable side wings 101 and adjustable front stops 102. The wings 101 are carried by the slotted bars 103 adjustable on the bottom by screws 104, while the stops 102 are adjustable on the rods 104 as will be clearly seen from Figs. 8, 10 and 11. The envelop receptacle is put into the sheet receptacle so that the side walls 95 rest on the bottom 100, 75 the wings 101 having been adjusted to the size of the envelop receptacle, and the front stops 102 moved to abut the front edge of the incline flaps 99, so that, when the envelops drop from the grippers, they fall on the 80 elevated bottoms 97 and then slide down over the flat irons 98 and come to rest on the inclined flaps 99 with their edges abutting the front stops 102. In Fig. 8, I have shown in dotted lines an envelop 105 just sliding 85 down onto the flaps 99.

The sheet receptacle is provided with hooks 106 and clips 107 which are adapted to fit around the stationary shaft 108 which latter is a part of the press and serves to 90 stiffen the construction thereof. The rods 104 are joined by a thin rod 190, Figs. 1, 8 and 9 and a connecting link 109 connects this rod 190 with a bar 109' which joins the levers 82 as seen in Fig. 1, so that as these 100 links oscillate the sheet and envelop receptacle are also oscillated around the said shaft 108 whereby the envelops or sheets are jogged into position for ready removal. The extent of the motion of the receptacles 105 may be adjusted by adjusting the jam nut 110 on link or rod 109 thus determining the incline of the receptacle.

The parts as above described contribute to the normal operation of the press and the 110 regular separating conveying, printing and delivering of two envelops at one time. If, however, one or both envelops fail to reach the platen, means are provided for tripping the press, which are as follows: A shaft 112, 115 see Fig. 3, is supported in arms 113 pivoted on shaft 45 and rotated upwardly at intervals by the arm 114, flexible connection 115, and bell crank 116 pivoted at 51. The bell crank carries a cam roll 117 co-acting with 120 the platen locking cam 53. The shaft 112 carries contacts 118 adapted to fall on fixed contacts 119 supported on a bar 120 and these parts are so timed in their operation that if one or both envelops fail to reach under the stops 46, the contacts will close. The closing of the contacts serve to close a circuit showing in Fig. 7, whereby a magnet 121 becomes energized and attracts its armature 122. As will be seen from Fig. 1, this 125 130

magnet is mounted on the hand lever 123 which is manually operated to trip the form whenever the operator so desires by the following instrumentality.

- 5 As is well known and old in the art, the form itself, not shown, is pivoted at 124 in eccentric 125 to which latter is connected arms 126 which in turn are connected to bell crank 127 by link 128. The bell crank is 10 provided with a groove 130 in which plays a pin 131, carried by an arm 132 on a shaft 133. Outside the frame this shaft is connected by an arm 134 to link 135, the other end of which is pivoted to the end of the lever 123 which is pivoted at 136. By means 15 of the aforesaid elements the form is tripped when the operator throws the hand lever, when the parts will assume the positions shown in Fig. 1. In the present instance, 20 however, the energizing of the magnet is utilized to throw the hand lever 123 automatically, thus tripping the form. To this end, an overbalanced latch 137 is pivoted on the lever 123, see Fig. 1, and connected by a 25 cord 138 or otherwise, to the armature 122. A lever 139 is pivoted at 140 to the connecting rod 5 on the left side of the press and this lever is provided with a hook 141 and a roller 142 and slides on the friction roller 30 143, carried by hand lever 123. The lever 139 slides normally back and forth with the connecting rod 5 but when the magnet is energized, the latch 137 is pulled down, the hook 141 engages the latch and thereby the 35 hand lever and throws the latter to trip the form. This happens when the lever 139 is moved to the right, on the return stroke, however, the aforesaid roller 142 engages the hand lever and thus automatically untrips 40 the press. The movable contacts 118 contact with the fixed contacts 119 only for the brief time when the cam roll 117 is on the low part of the cam 53. At all other times the circuit is open. And of course the 45 operator can at any time operate the hand lever. Thus it will be clear that when one or both envelopes miss, the form is tripped and will remain tripped as long as only one or no envelopes are fed to the platen. However, 50 if only one envelop misses, the other one will pass through the press, but will not be printed, hence means are provided for delivering this unprinted envelop separate from the printed ones. These means will 55 now be described, see Figs. 1, 8, 9, 10, 13, 14 and 15.
- On the rods 104 and right in front of the envelop receptacle is placed a framework 145 which supports the shafts 146 and 147 60 which are connected by two arms 148 and a link 149, so that when one shaft is rotated the other one must rotate. The shaft 147 carries a wing or blade 150. On the shaft 146 is fastened a collar 151 having an arm 65 152, which latter carries a bell crank pivoted

freely at 153. The one arm 154 of said bell crank projects upwardly on the one side of arm 152, while the other arm 155 of the bell crank is on the other side of the arm 152 and provided with a cam surface 156 and catches 157 and 158 adapted to engage the arm 152 as shown. On either side of the collar 151 there is a spring roller, the one of which 159 is wound with a tape 160, and on the side toward the collar 151 the roller carries a circular flat spring 163 having a button 164. The other end of the tape 160 is made fast to a hook 165 screwed in the shaft 133, which is a part of the tripping mechanism. Normally the tape 160 is taut between the hook 165 and the spring roller 159 and tends to pull the latter in an anti-clockwise direction in Fig. 13 and against the action of the spring 166. A stop 161 on the roller abutting a fixed stop 162 limits the pull of the tape 160 and keeps the roller in the position shown in Fig. 13 in which the spring 166 tends to move the roller 159 in a clockwise direction. On the other side of the collar 151 the other spring roller 167 is located which is wound with a tape 168, the other end of which is made fast to the rod 169 carried by the lever 82 and which supports the one end of the spring 92. This rod of course moves with the lever 82, hence the roller 167 is constantly oscillated through the arc 175 by the united actions of the tape 168 and the spring 170. The stops 171 and 172 limit the action of the spring. A lug 173 is fast on the roller 167 and moves therewith. On the framework 145 is fast a stationary cam 174. The operations of these parts are as follows, it being kept in mind that when the arm 152 is moved the blade 150 is also swung over, the rotating of the shaft 147 being limited by the grip of a flat spring 179 acting on the flat surfaces provided on roller 180 fast on said shaft and shown in Fig. 8. The normal positions of the parts are as shown in Fig. 13. Now, when the form is tripped the tape 160 is slackened as shown in Fig. 1 and the spring 166 carries the roller 159 in the direction of arrow 176 almost a complete revolution until the stop 161 again abuts the stop 162 on the right side thereof, the flat spring 163 sliding over the cam surface 156 in passing the same. Next the form and platen move apart, the grippers travel toward the latter to seize the one unprinted envelop thereon, the press is untripped, the tape 160 is pulled taut by the hook 165 and the roller 159 is rotated back to the position shown and the button 164 moving in the direction of the arrow 177 engages the arm 152 and rotates the latter and thereby swinging the blade 150 over into the dotted position shown in Fig. 8, and during this backward movement the spring 163 passes back of the cam 174 leaving the arm 155 and the arm 152 in a 130

raised position, held thus by the flat spring 179. Next the grippers with the envelop move to the right, the grippers are opened and deposit the unprinted envelop on the blade 150. As the grippers now again travel toward the platen the tape 168 is tightened and the roller 167 with its lug 173 is rotated and the latter engages the raised arm 154 on the arm 152 and returns this latter to the former position as shown in Fig. 13 thereby swinging the blade 150 back to its normal position and the unprinted envelop is deposited in the pocket 178, which is located directly in front of the envelop receptacle as seen in Figs. 1, 8 and 9. If the next envelop misses the press is again tripped and the above operations are repeated, but the blade 150 is immediately returned to receive the next unprinted envelop because the arm 154 of the bell crank is pulled out of the way of the lug 173 by the button 164 as shown in Fig. 15, which illustrates the position of the parts in the moment the lug 173 passes the arm 154 and the button 164 is withdrawn from the latter by the stationary cam 174. From this position the lug 173 continues its travel a short distance and then returns to its position as shown in Fig. 13, while the arm 154 drops inwardly until the stop 157 rests on the arm 152. This puts the arm 154 in position to be engaged by the lug 174 when the tripping occurs again. Thus all the unprinted envelops are deposited in the pocket 178.

The above is thought to fully describe my invention and the operation thereof, and changes may of course be made without departing from the scope of the claims.

I claim:

- 46 1. In a printing machine the combination of an oscillating delivery mechanism, a tripping mechanism, a rotatable delivery member adapted to be rotated in one direction by the said tripping mechanism and to receive the unprinted matter from the said oscillating delivery mechanism, and means operated by the latter for rotating the said delivery member in the opposite direction and delivering the said unprinted matter.
- 50 2. In a printing machine having a platen, the combination of means for feeding two envelops side by side to the said platen, means for tripping the said machine when one of said envelops fails to reach the said platen and means actuated by the said tripping means for delivering the other envelop.
- 55 3. In a printing machine having co-operating printing members, the combination of means for conveying two envelops side by side to the said members to be printed and means for preventing the one envelop from being printed if the other envelop fails to reach the said conveying means.
- 60 4. In a printing machine the combination of a conveying mechanism for conveying

two envelops side by side, means for printing the said two envelops and means for preventing the one envelop from being printed if the other envelop fails to be acted upon by the said conveying mechanism.

5. In a printing machine the combination of a conveying mechanism for conveying two envelops side by side, means for printing the said two envelops and means for preventing the one envelop from being printed if the other envelop fails to be acted upon by the said conveying mechanism, and means for conveying the one single envelop through said machine.

6. In a printing machine having a platen and a form member the combination of means for feeding two envelops side by side to the said platen, means for tripping the said form member when one of the said envelops fails to reach the said platen and means for delivering the other unprinted envelop.

7. In a printing machine the combination of means for feeding two envelops side by side and means for delivering the one of said envelops separate from the printed envelops if the other of the said envelops fails to be fed.

8. In a machine of the class described the combination of a platen, means for feeding two envelops side by side to the said platen, means for delivering the said envelops, a separate delivery member and means for actuating the said second delivery member when one of the said envelops fails to be acted upon by the said feeding means.

9. In a machine of the class described the combination of a platen, a feeding mechanism for feeding envelops side by side to the said platen, a delivery mechanism, a delivery member for receiving the unprinted envelops from the said delivery mechanism and means for actuating the said delivery member when one of the said envelops fails to be acted upon by the said feeding mechanism.

10. In a machine of the class described the combination of a platen, a feeding mechanism for feeding envelops side by side to the said platen, a delivery mechanism, a delivery member for receiving the unprinted envelops from the said delivery mechanism and means for actuating the said delivery member when one of the said envelops fails to be acted upon by the said feeding mechanism, and a separate receptacle for receiving the unprinted envelop from the said delivery member.

11. In a machine of the class described the combination of means for simultaneously printing two envelops, means for preventing the one envelop from being printed if the other one fails to be placed in printing position and a delivery mechanism adapted to deliver at one point either both of the said

70

110

115

120

125

130

envelops if the same are printed or to deliver the one single envelop at another point if the other single envelop fails to be placed in printing position.

- 5 12. In a machine of the class described the combination of a platen, means for simultaneously placing two envelops on the said platen to be printed, a delivery mechanism for removing the envelops from the platen, 10 a second delivery member and means for actuating the latter to receive one of the envelops from the said delivery mechanism when only one envelop reaches said platen.

13. In a machine of the class described the 15 combination of a delivery mechanism, means for conveying a plurality of envelops through said machine and to the said mechanism and a second delivery device for receiving the envelops from the said delivery 20 mechanism in case only one of the said envelops reaches latter position.

14. In a machine of the class described the combination of means for delivering printed matter, a tripping mechanism, a device 25 normally inactive for delivering unprinted matter and means actuated by the said tripping mechanism for rendering the said inactive device active when the said matter fails to be printed and to cause the 30 said device to receive the unprinted matter from the said delivery means.

15. In a printing machine the combination of a delivery mechanism, a tripping device, a member normally inactive and means 35 for actuating the said member by the said tripping device to receive the unprinted matter from the said delivery mechanism and means actuated by the latter for restoring the said member to its normal position.

- 40 16. The combination of coöperating movable printing members, a receptacle for receiving the unprinted matter separate from the printed matter, a rotatable member,

means for causing the latter to be actuated to receive the unprinted matter after the 45 same has passed through the machine and means operated by one of the said printing members for causing the said rotatable member to deliver the said unprinted matter to the said receptacle. 50

17. The combination of coöperating printing members, a receptacle for receiving the unprinted matter separate from the printed matter, a rotatable member, means for causing the latter to be actuated to receive the 55 unprinted matter after the same has passed between the said printing members and means operated by one of the said printing members for causing the said rotatable member to deliver the said unprinted matter to 60 the said receptacle.

18. In a printing machine the combination of means for conveying two envelops side by side to be printed, means for delivering said envelops when printed, means for 65 tripping the machine if one of the envelops fails to be printed and means actuated by the said tripping mechanism for delivering the unprinted envelop at a point different from the one where the printed matter is 70 delivered.

19. The combination of coöperating printing members, means for feeding two envelops or sheets side by side to the same, a delivery mechanism, a rotatable member 75 moving with the said mechanism, means for actuating said member while it moves to receive the one envelop or sheet from the delivery mechanism if the other envelop or sheet fails to be printed. 80
